DESIGN FOR A PLATE

James Henry Wilson, Altoona, Pa., assignor to
The National Toddle House Corporation, Memphis, Tenn., a corporation of Delaware

Application August 25, 1939, Serial No. 86,894

Term of patent 14 years

To all whom it may concern:

Be it known that I, James Henry Wilson, a citizen of the United States of America, residing at Altoona, in the county of Blair and State of Pennsylvania, have invented a new, original, and ornamental Design for Plates, of which the following is a specification, reference being had to the accompanying drawing, forming a part thereof, in which the single figure is a top plan view of a plate, showing my new design, a repeat unit of which is indicated between the dotted lines, it being understood that the ornamentation is continued throughout the border of the plate.

I claim:

The ornamental design for a plate, as shown and described.

JAMES HENRY WILSON.
